(57) **CLAIM**

The ornamental design for a hybrid airship-aerostat, as shown and described.

DESCRIPTION

FIG. 1 is a front, side perspective view of the hybrid airship-aerostat in accordance with the present design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, right perspective view of the hybrid airship aerostat of FIGS. 1-7, illustrating the hybrid airship-aerostat docking into a mooring platform.

The broken lines shown in the drawings illustrate portions of the hybrid airship-aerostat that form no part of the claimed design.

1 Claim, 7 Drawing Sheets
